(57) **CLAIM**

The ornamental design for a slitter tool, as shown and described.

DESCRIPTION

FIG. 1 is a right side view of a slitter tool.

FIG. 2 is a left side view of the slitter tool.

FIG. 3 is a top view of the slitter tool.

FIG. 4 is a bottom view of the slitter tool.

FIG. 5 is a rear view of the slitter tool; and,

FIG. 6 is a front view of the slitter tool.

The broken line showing is for environmental purposes only and forms no part of the claimed design.
